UNITED STATES PATENT OFFICE.

HARRY A. TAYLOR, OF NEW YORK, N. Y.

DESIGN FOR A LADIES' UNDERVEST OR SIMILAR UNDERGARMENT.

47,658.

Specification for Design. Patented July 27, 1915.

Application filed January 9, 1915. Serial No. 1,466. Term of patent 7 years.

To all whom it may concern:

Be it known that I, HARRY A. TAYLOR, a citizen of the United States, residing at the borough of Manhattan, city, county, and State of New York, have invented a new, original, and ornamental Design for a Ladies' Undervest or Similar Undergarment, of which the following is a specification, reference being had to the accompanying drawings, forming part thereof.

showing my new design; Fig. 2 is a view, much enlarged for the sake of more clear illustration, of that part only of the garment which is novel.

I claim:

The ornamental design for a ladies' undervest or similar undergarment.

HARRY A. TAYLOR.
